UNITED STATES PATENT OFFICE.

ROBERT P. FADDIS, OF SOCORRO, TERRITORY OF NEW MEXICO.

RAILWAY.

SPECIFICATION forming part of Letters Patent No. 398,037, dated February 19, 1889.

Application filed September 17, 1888. Serial No. 285,651. (No model.)

To all whom it may concern:

Be it known that I, ROBERT P. FADDIS, of Socorro, in the county of Socorro, Territory of New Mexico, have invented a new and useful Improvement in Railways, of which the following is a specification.

My invention is an improvement in railways; and it consists in certain novel constructions and combinations of parts, as will 10 be hereinafter described and claimed.

In the drawings, Figure 1 is a cross-sectional view of a track embodying my improvements. Figs. 2 and 3 are cross-sectional views of my invention, illustrating slightly-different 15 constructions. Figs. 4 and 5 are detail views, and Fig. 6 is a side elevation.

In the present invention I employ cribs A, having end plates, A', and side connecting- 20 rods, A², and base connecting-rods, A³, extending between said end plates and short ties or rail-seats B in such cribs, substantially as shown in my former application, Serial No. 274,614, filed May 19, 1888; and I do not herein broadly claim such construction of the crib, as 25 it forms a part of the subject-matter of the claims of my former application, above described.

The rail C is rested on the seats B, and is secured in the manner hereinafter specifically 30 described.

The manner of fastening the rails is a distinctive feature of my present invention, differing from my former construction in that, instead of securing the rails to the short ties 35 or rail-seats and then securing the said rail-seats to the crib-frame, I secure such rails directly to the crib-frame, and preferably by connections which extend down and connect with the lower or base connecting-rods of the 40 said crib, so that the fastening of the rails will clamp the rail-seats firmly in place and make the crib-frame, short blocks or rail-seats, and rail into practically a solid body, increasing the solidity and firmness of the construction. 45

In carrying out the invention I employ anchor-rods D, connected with and extending between the lower portion of the crib-frame and the rails, uniting such parts, as shown. 50

In the practice of the invention with rails especially constructed therefor it may be pre-

ferred to form openings through the base of the rail for the anchor-rods, as shown in Fig. 2; but in the use of the invention with the usual rail the clamp-plate E, as shown in Fig. 55 3, having portions e to grip the rail, and lugs e', for the connection of the anchor-rods, or constructions equivalent to said plates E, may be found desirable. By preference I connect the anchor-rods at their lower ends to the 60 base connecting-rods of the crib-frame, and it is also preferred to extend such anchor-rods diagonally downward and inward from the opposite sides of the rail, bracing and securing the rail after the fashion of strut-braces. 65

The anchor-rods D may be made in sections joined together at d, and looped at their lower ends around the base connecting-rods, as shown in Fig. 2; or they may be formed in a single piece hooked at their lower ends around 70 the lower base-sections, as shown in Fig. 3, and being suitably secured at their upper ends by nuts, so they may be put in place or removed without disturbing the rail.

The tie rods or bars G, which extend between the opposite rails of a track, have their outer ends provided with hook-like portions g, to engage upon the outer edge of the base of the rail A. At the inner edge of said rail I secure on the bar G a plate, G', which 80 laps on the inner portion of the base of the rail, and is secured to the bar G by a rod, H, which extends diagonally downward and outward, and is suitably secured at its lower end, preferably to the outer connecting-rod of the 85 crib-frame, as shown.

While, as before stated, I prefer to arrange the anchor-rods diagonally, as shown, it is obvious they might be arranged on the same side, or practically vertical, and I do not desire in 90 the broad features of my invention to be restricted to said diagonal arrangement.

Having thus described my invention, what I claim as new is—

1. In a railway, the combination of the crib-frame, the rail seat or seats therein, the rails on said seats, and the anchor-rods passed through openings in and secured to the base of the rail at the opposite sides of the latter, and extended thence and secured to the lower 95 portion of the crib-frame, substantially as set forth.

2. In a railway, the combination of the rail, the crib-frame having lower or base connecting-rods, and the anchor-rods connected at one end with the rail at the opposite sides 5 thereof, and extended thence and connected with the base-rods, substantially as set forth.

3. In a railway, the combination, with the crib-frame and the rails, of the connecting-rods connected with the rail at the opposite 10 sides of same and extended diagonally downward and inward, substantially as and for the purposes set forth.

4. In a railway, the combination of the crib-frame having base connecting-rods A³ and

the rail seat or seats in said frame, the rail 15 and the anchor-rods extended diagonally between and connected with the base connecting-rods and the rail, substantially as set forth.

5. In a railway, the combination of the crib-frame, the rail seat or seats, the cross-bar G, 20 having hook g, the plate G', and the rod H, all constructed and arranged substantially as and for the purposes specified.

ROBERT P. FADDIS.
